UNITED STATES PATENT OFFICE.

MARTIN ROTELLINI, OF NEW YORK, N. Y., ASSIGNOR TO HALCOLITE COMPANY, INC.,
A CORPORATION OF NEW YORK.

DESIGN FOR A LIGHTING-FIXTURE PLATE OR ARTICLE OF ANALOGOUS NATURE.

Application filed December 12, 1928. Serial No. 29,229. Term of patent 7 years.

To all whom it may concern:

Be it known that I, MARTIN ROTELLINI, a subject of the King of Italy, and a resident of borough of Brooklyn, New York, county of Kings, and State of New York, have invented a new, original, and ornamental Design for a Lighting-Fixture Plate or Article of Analogous Nature, of which the following is a specification, reference being had to the accompanying drawing, forming a part thereof.

In the drawing:

Figure 1 is an inverted plan view of the lighting fixture plate or article of analogous nature, the parts shown in full line outline being ornamented in the same manner as the parts more fully illustrated;

Figure 2 is a side view of the same.

I claim:

The ornamental design for a lighting fixture plate or article of analogous nature substantially as shown and described.

MARTIN ROTELLINI.
